ATTORNEY.

UNITED STATES PATENT OFFICE.

JACK T. COSMAN, OF NEW YORK, N. Y.

DESIGN FOR A TYPE-WRITER FRAME.

52,696.

Specification for Design.

Patented Nov. 19, 1918.

Application filed December 17, 1917. Serial No. 207,632. Term of patent 14 years.

To all whom it may concern:

Be it known that I, JACK T. COSMAN, a citizen of the United States, residing at New York, in the county of New York and State of New York, have invented a new, original, and ornamental Design for Type-Writer Frames, of which the following is a specification, reference being had to the accompanying drawing, forming part thereof.

The figure is a perspective view of my improved typewriter frame.

I claim:

The ornamental design for a typewriter frame as shown.

JACK T. COSMAN.

Witnesses:

H. WATSON,
J. K. ULRBERG.
